CLAIM

The ornamental design for an display panel for a machine tool with graphical user interface, as shown and described.

DESCRIPTION

FIG. 1 is a front view of an display panel for a machine tool with graphical user interface, showing a first embodiment of our new design;

FIG. 2 is an enlarged front view of the display part shown in FIG. 1;

FIG. 3 is a top view of the display panel for a machine tool with graphical user interface shown in FIG. 1;

FIG. 4 is a bottom view thereof;

FIG. 5 is a right side view thereof;

FIG. 6 is a left side view thereof;

FIG. 7 is a back view thereof;

FIG. 8 is a front view of an display panel for a machine tool with graphical user interface, showing a second embodiment of our new design;

FIG. 9 is an enlarged front view of the display part shown in FIG. 8;

FIG. 10 is a top view of the display panel for a machine tool with graphical user interface shown in FIG. 8;

FIG. 11 is a bottom view thereof;

FIG. 12 is a right side view thereof;

FIG. 13 is a left side view thereof; and,

FIG. 14 is a back view thereof.

(Continued)

The broken lines in the drawings depict environmental subject matter only and form no part of the claimed design.
